CLAIM

The ornamental design for an integrated conduit and interface box for a motor, as shown and described.

DESCRIPTION

FIG. 1 is a front perspective view of an integrated conduit and interface box for a motor showing our new design; FIG. 2 is a side elevation view thereof, with the opposite side being a mirror image; FIG. 3 is a front elevation view thereof; FIG. 4 is a rear elevation view thereof; and, FIG. 5 is a top plan view thereof. The broken lines shown represent unclaimed subject matter and form no part of the claimed design.
